UNITED STATES PATENT OFFICE.

THEODORE POWLIN, OF WEST MARTINSBURG, NEW YORK.

RAIL-JOINT CONNECTOR

1,282,935.

Specification of Letters Patent. Patented Oct. 29, 1918.

Application filed May 10, 1918. Serial No. 233,637.

To all whom it may concern:

Be it known that I, THEODORE POWLIN, a subject of the Emperor of Austria, resident of West Martinsburg, county of Lewis, and 5 State of New York, have invented certain new and useful Improvements in Rail-Joint Connectors, of which the following is a specification.

This invention relates to improvements in 10 connecting ends of rails, as used upon steam and street railroads.

The principal object of the invention is to provide means whereby the abutting ends of the rails may be held positively together 15 and prevented from separating.

A further object is to provide a device for connecting the abutting ends of rails without the use of bolts, plates or other engaging means, it being merely necessary to insert 20 the securing element and move the rails into close contact.

A still further object is to provide means whereby the connecting elements may be readily withdrawn and the rails separated 25 when desired.

These and other like objects are attained by the novel construction and combination of parts hereinafter described and shown in the accompanying drawings, forming a material 30 part of this disclosure, and in which:—

Figure 1 is an enlarged fragmentary side elevational view of a pair of abutting rails, partly broken away in order to show the construction.

35 Fig. 2 is a horizontal sectional view, taken on line 2—2 of Fig. 1.

Fig. 3 is a transverse sectional view, taken on line 3—3 of Fig. 2.

40 Fig. 4 is a fragmentary sectional view, showing the end of an abutting rail, prior to the insertion of the engaging elements, and

Fig. 5 is a perspective view, showing the main connecting element in detail.

45 The rails used are of the usual rolled type of construction, consisting of a head 14, central stem or web 15, and base flange 16.

These rails are extended laterally upon 50 both sides of their webs, adjacent to their ends, to a thickness slightly less than the head 14, of the rail and formed in the thickened extensions 18 are central rectangular openings 20, so that the openings in adjacent rails register.

55 Secured in these openings upon one side thereof, by the rivets 21, are the ends of re-

silient detents 22, the same having thickened terminals 23, near which are rigidly engaged rods 24, the same having angularly bent ends 25 extending outward through 60 openings 26, leading from the recesses 20 outward through the thickened portion of the rail end.

The connecting element comprises a rigid bar 30, reduced toward its ends 31, and 65 formed with hook catches 32, upon opposite sides adapted to engage with the extremities 23 of the spring detents, the faces of the catches 32 being slightly beveled so the corresponding ends of the spring detent may 70 readily engage therein.

In operation, the detents 22, having been secured in the ends of the rails, in the manner shown, the bar 30 is entered within one of the openings, and the adjacent rail is 75 passed over the opposite extending end. As the rails are brought together, so as to form a close joint between their abutting ends, the ends 23 of the detents engage the hook catches 32, holding the bar rigidly in 80 position and maintaining the abutting ends of the rail against separation.

When it is desired to release the rails, the outstanding end 25 of the rod set in the spring detent is drawn outward by the insertion 85 of a bar or like object, retracting the detents from engagement with the bar, permitting the rails to be separated in an obvious manner.

From the foregoing it will be seen that an 90 extremely quick and secure fastening means has been described.

Having thus described my invention what I claim as new and desire to secure by Letters Patent, is—

1. In a rail joint, the combination with 95 a pair of abutting rails having central longitudinal recesses extending inward from the ends thereof, a bar adapted to enter the mentioned openings, and opposed spring detents 100 fixed in the openings, said detents being adapted to engage with the ends of said bar, whereby it is held in position and the rails held against separation.

2. In a rail joint connection, the combination 105 with a pair of running rails having enlarged stems at their ends and containing longitudinal openings which extend inward from the ends thereof, a pair of spring detents, one of said detents being secured in 110 each of the mentioned openings and extending rearwardly therein, a bar having hooked

ends adapted to engage with said detents, said bar being suited to the mentioned openings, and means to retract said detents whereby said bar may be released.

- 5 3. In a rail joint connection, the combination with a pair of running rails having thickened stems adjacent to the ends thereof, recesses extending in from the ends of said rails in said thickened portions, resili-
10 ent detents secured within said openings, said detents extending rearwardly and pressing toward the opposite side of the opening

in which they are secured, a bar adapted to enter said openings, means formed with said bar adapted to contact with said spring de-
15 tents, whereby the rails are held in operative position, and means on said detents extending outwardly through said rails by which the detents may be withdrawn from contact with said bar.

20 In testimony whereof I have affixed my signature.

THEODORE POWLIN.
